UNITED STATES PATENT OFFICE.

MARCEL TOURNIER, OF PARIS, FRANCE.

MUSICAL INSTRUMENT.

Application filed April 29, 1926, Serial No. 105,358, and in France May 7, 1925.

This invention relates to mechanisms for producing sustained vibrations of stringed musical instruments. It concerns itself more especially with the production of sustained vibrations in the strings of pianos and instruments of the same class.

In prior devices of this kind, it has been common to produce vibrations by providing each piano string of the same sound with an electromagnet supplied with current of the same period as that of the string to which it is related. Devices of this kind are generally bulky and complicated inasmuch as e. g. in a piano 88 separate sources of periodical current with proper distributing and interrupting mechanisms must be provided (one for each note).

The principal object of the present invention is to reduce materially the number of electrical sources necessary to make all of the notes in a piano or similar instrument vibrate in a sustained manner.

This object is obtained by means of the constructions illustrated in the following drawings in which:—

Fig. 1 shows schematically an alternating source of current arranged to provide a periodical current having harmonics capable of actuating a series of electromagnetic vibrators connected in parallel.

Fig. 2 illustrates diagrammatically an alternating current source derived from a neon lamp, amplified by a 3 electrode lamp and distributed to a group of electromagnetic vibrators arranged in series.

Fig. 3 shows the form of the primary current curve for the apparatus shown in Fig. 2.

Fig. 4 shows, diagrammatically, a mechanical vibrator to be used in one modification of the invention.

Fig. 5 shows schematically an ensemble of vibrators arranged according to Fig. 3 attached to function with a piano.

Fig. 6 shows a system of vibrating relays to be used in another modification of the invention.

Fig. 7 shows a single electrical relay actuating contact making vibrating parts of different frequency.

The present invention, in common with prior devices of this class, sustains the vibration of strings by means of individual electromagnetic vibrators arranged in connection with each of the strings of the same sound. It differs from prior art devices in combining into a single circuit a certain num-

ber of the electromagnetic vibrators. The manner in which this is accomplished is briefly, as follows: A group of strings which are (preferably) harmonics of some "fundamental" string or note, may be selected and each provided with electromagnetic vibrators; the key on the piano corresponding to each string sound is connected in circuit with its vibrator so that the depressing of the key sends current into the vibrator from an electrical source. This electrical source is arranged to provide current of a convenient fundamental frequency corresponding to that of the "fundamental" string or note and has eventually superposed thereon harmonic frequencies corresponding to the periods of the other strings in the group.

Thus if all the C's (seven in number) in a piano are grouped together, any one of the C's may be sounded from a single source of current. The C sharps may similarly be grouped in a second circuit fed from a second source. The D's in a third group etc. Thus, instead of 88 separate sources of current, only 12 will be necessary.

In the same way a series note C₁, C₂, G, etc. which are harmonics of one another in the relation of 1, 2 and 3 times the fundamental or D₁, D₂, A etc., may be grouped with a single source of periodical current containing the harmonics required and any note in the said series can be sounded from such a single source, an arrangement of this kind may include notes having 6, 12 etc. times the fundamental and the whole range of the piano covered with only 7 sources of current.

Finally, if the fundamental frequency is that, let us say, of middle C and one groups with it the C two octaves higher C i. e. if one includes notes having frequencies 1, 4, 5 and 6 times the fundamental it will be possible to group 3 notes in each octave with such fundamental and all the notes on the piano can be provided with periodical current from 3 separate sources.

Using any one of the above arrangements, one can ascertain whether any given current source contains a desired harmonic and whether it is present in the desired intensity by making of the well-known analytical method of Fourier or by testing its effect in the circuit selected. In the latter case, if the frequency of the fundamental current wave is found to correspond to that of the "fundamental" string, the correspondence between the selected harmonics will be present as well.

The foregoing principle underlying the invention may be carried out in practice in any one of a number of ways.

One can, for example, utilize as a current source an alternator a , supplying current of appropriate composite wave form to feed electromagnetic vibrators attached in a common circuit to a group of 7 or 14 or 21 string sounds. The vibrators can be arranged in parallel across the alternator terminals as shown in Fig. 1, the switches c^1 , c^2 , c^3 , etc. closing the circuits to the vibrators when the keys are depressed. This parallel arrangement of the circuits is best adapted to a high-power current source having a low resistance.

One can also use as a current source 3-electrode lamps having grid and plate circuits comprising wires of high resistance, the coupling "grid-plate" being very tight and the self-induction having a large distributed capacity or two lamps may be coupled by means of capacities and resistances in the manner of an Abraham multivibrator system. With either of these arrangements the current source may be given a wave form corresponding to the string grouping desired. An analogous system for synthesizing current of appropriate wave form consists in employing the periodic discharge from a neon lamp as current source (Fig. 2). To accomplish this, a source of direct current d is provided and one of its poles connected first to one of the two plates of a condenser e and then to one terminal of neon lamp f . The other pole of d is connected through a resistance g to the other plate of condenser e . The second terminal of lamp f is connected through the primary h^1 of a transformer to the other of the two plates of condenser e . The neon lamp resists the passage of current long enough to permit the condenser e to become charged but when the tension has risen sufficiently, the lamp suddenly discharges and the current stored in e flows through the primary circuit h^1 . The form of discharge curve is shown in Fig. 3. The current flowing in h^1 may be utilized by means of a secondary h^2 of the above said transformer. The ordinary neon lamp yields a current which is somewhat too weak. It may be amplified by means of the 3-electrode lamp i , fed by a main battery j (the usual battery for the filament is not shown in Fig. 2). The amplified current thus produced may be led from the lamp j to the electromagnetic vibrators b^1 , b^2 , b^3 arranged in series therewith, the switches v^1 , v^2 , v^3 short circuiting the vibrators when the latter are not functioning. It suffices only to open any of the switches in order to direct current from the source into the vibrator. As the resistance of lamp i is great in respect to that of the vibrators b^1 , b^2 , b^3 the strength of the current will remain substantially the same whether one or several switches are opened.

If it is desired to use a mechanically ac-

tuated vibrator as a current source, it is only necessary to provide a number of main vibrators maintained constantly in vibration and to link to every one of such vibrators contact controlled by the latter. A current source of this kind is shown in Fig. 4. It comprises a frame k preferably (of aluminium) the base of which comprises a journal k^1 for a shaft l^1 which can be turned by means of a wheel l^2 and a worm l^3 controlled by a hand wheel l^4 . The foregoing elements serve to distend a spring m attached to an iron or similar paramagnetic bar n . Bar n is suspended from two cords o^1 and o^2 attached to the top of frame k the cords being able to conduct current from k to n . One end of the bar n carries a short, strong elastic element n^1 provided with a contact point of tungsten or similar non-oxidizable material. n^1 presses lightly, when the main vibrator n is not in action, against an adjustable screw p provided with a tungsten contact and supported by an insulating block on frame k . A U-shaped electromagnet is fastened in any appropriate manner to frame k and the free ends of the magnet are arranged to terminate on opposite sides of vibrator n so that the latter, and with it element n^1 may be angularly displaced by the electromagnet q if the latter is magnetized. Bar n has a period of vibration which may be adjusted by changing the tension of spring m and it is only necessary to establish a circuit from one pole of a battery s to the mass of frame k , the current finding a path through o^1 or o^2 , to bar n , part n^1 , contact screw p , winding of electromagnet q and back to battery s in order to cause bar n to vibrate at the desired frequency. A second short strong elastic element n^2 is fastened to the bar n and comes into contact with an adjustable screw r which is supported by an insulating block fastened to frame k . The contact n^2 , r is utilized to control the emitting of the current to be utilized in the electromagnets placed over the piano strings. A complete layout, using the above described mechanical vibrator is partially shown in Fig. 5. It includes a battery s serving to furnish current to a group of, let us say 12 vibrator bars such as n and also to actuate the electromagnetic vibrators such as b^1 placed over the piano strings (Fig. 5 showing only 3 bars n) all the vibrating bars n being connected to one pole of battery s (negative) and all the electromagnetic q and contact screws p to the other pole. The electromagnetic vibrators such as b^1 which are placed above the piano strings t are each connected into a circuit consisting of the electromagnet b itself, of a switch c^1 (in grand pianos and the like, these are connected to the dampers which are displaced by depressing the keys), a wire connected to a slideable contact u (adjustable onto any one of plots connected to the electrodes of the battery s) the part of battery s which remains active be-

yond contact u (in Fig. 5 it comprises that part of the battery which is to the right of slidable contact u), one extreme pole of the battery (this pole being connected to all the 5 vibrating bars n), a bar n , the contact element n^2 , the contact screw r and a return wire to the electromagnet b^1 . A single bar n furnishes current not only to one vibrator b^1 for one sound as shown in Fig. 5, but for 10 instance also to six others (seven in all) connected in parallel between contact screw r and slidable contact u in the manner, shown in Fig. 1. To avoid excessive sparking, a condenser (not shown) may be connected in parallel between n^1 and p and condenser v between n^2 and r . As shown in Fig. 15 5, a resistance w may be connected to the condensers v attached across n^2, r . By suitably choosing the capacities of condensers v and the resistance of elements w this circuit may be made to furnish the harmonic desired for any particular electromagnetic 20 vibrator.

The vibrators b^1 and switches c^1 may, in a 25 grand piano be arranged in zig-zag lines on a board placed transversally over the piano strings. The set of vibrating bars n is located in a box which is a distinct part from the piano and may occupy any convenient place near the same.

From the preceding description, it will be 30 clear that current source s cause bars n to vibrate without interruption and the elements n^2 of bar n will tend to send a periodical current into the electromagnets b . However no current will actually flow into b^1 as long as the proper piano key is not depressed. An electromagnet b^1 on receiving of proper periodical current may vibrate its 35 corresponding string even directly without the intervention of hammers or else it may maintain the vibration of the string after the hammer has struck the said string. The strength of the sound maintaining effect 40 may be regulated by adjustment of the slid- able contact u or else by the action of a slid- able contact of a modulating rheostat ar- ranged in the circuit, said slidable contacts being arranged to be moved by the knee or 45 the foot in order to variate the "expression" of the tune produced.

Although apparatus constructed in accord- 50 ance with the foregoing reduces materially the number of parts heretofore necessary in apparatus of this kind it still offers a cer- 55 tain amount of inconvenience on account of the bulk of the box for the vibrating bars n . First of all, it may be taken into account that the number of ampere-turns necessary 60 for the electromagnetic vibrators is far from negligible about 500 ampere-turns being generally required. Contacts n^2 , as a conse- 65 quence, are subjected to severe usage and must be provided with rather large contacts

i. e. with contacts of about 3 mm. in diameter 65 and 1 mm. in thickness. It is further necessary that the period of own vibration of the strong elastic elements n^1 and n^2 be quite high in respect of that of the corresponding bar n so that the vibrations of n^1 and n^2 70 should not effect materially the period of vi- bration of bar n which period ought to be in- dependent of the amount of the amplitude of n . The elements n^1 and n^2 must therefore be rather rigid and heavy. But in spite of 75 this the vibrating period of bar n should be uniquely dependent on the tension in spring m . This postulates rather heavy and power- 80 ful springs m which must be able to exert a pull of 7 to 40 kilograms. Frames k 80 must, consequently, be made large—about 30 cm. x 15 cm. The total bulk of the box con- 85 taining the vibrating apparatus is thus rather great. It may, however, be reduced by means of the following construction.

Referring to Fig. 6 of the drawing, there is shown a small "standard" vibrating ele- 90 ment having a period "x" which may be regu- 95 lated to a nicely by means of a small spring 2. The standard 2 is maintained in a state of uninterrupted vibration by means of an elec- 100 trical source 3 having one terminal connected to a small electromagnet 4 acting as a relay and arranged to attract an elasical contact bearing strip 7, called a relay strip. The 105 standard vibrating element 1 when not drawn by electromagnet 4, contacts with adjustable screw 5. The second terminal of 3 is connected through the relay electromagnet 6 to the fixed end of "standard" 1. The current 110 necessary for vibrating 1 being weak contacts on 1 and at 5 need not be large. The "standard" vibrator 1 itself may also be made of small and light construction. The 115 relay strip 7, heavier than 1, is placed in front of relay magnet 6 and provided with a contact large enough to carry current to mag- 120 nets b^1 . This last mentioned contact seats when the relay magnet 6 is not excited, against contact r connected through switch c^1 to electromagnets b^1 . Current for said electromagnets b^1 may be furnished by a sep- 125 arate source of current s , as in the construc- 130 tion shown in Fig. 5. The contact 7, r will make and break in step with the "standard" 135 vibrator 1. As long as switch c^1 , operated by the key, is not closed, vibration of 7 relatively to r takes place without flow of current. On the contrary, as soon as c^1 closes, current of suitable periodical nature flows to electromag- 140 net b^1 and causes string t to vibrate. The construction, briefly, provides a relay system in which the dimensions of the "standard" 145 vibrators 1, and consequently the dimensions of the whole vibrator box, are very materially 150 reduced.

The electrical relay strip 7 may be arranged so as to have a different own fundamental

period than the standard vibrator 1 itself. If the frequency of 1 is taken as "y" 7 may be given a frequency of "4 y". A frequency "y" for 1 can be made to efficiently vibrate strip 7 having a frequency "4 y". But a frequency "4 y" in 7 enables the latter to vibrate much more easily a string having a high frequency for instance a frequency of "8 y" than it could if it had a frequency of "y" only. A frequency "8 y" is only a second harmonic of "4 y" but an 8th harmonic of "y". As a result of this arrangement high notes can be sustained in a much stronger manner than would otherwise be the case. Thus 6 may function to produce currents identical to standard 1 or currents showing a different main period. A relay electromagnet 6 may be arranged as shown in Fig. 7 in order to be excited by a current of frequency "y" and to vibrate at one pole a contact strip 7 with a frequency "4 y" and at the other pole in another contact strip 8 at a frequency of only "y". The relay magnet 6 may be supplied with pulsatory or alternating current supplied from any convenient source for example, by a standard vibrator or buzzer 1 as shown in Fig. 6, or it may be fed by a 3-electrode oscillator x as shown in Fig. 7. In the latter case it is preferable to mount the lamp circuits on an iron base in order to obtain low frequencies.

From the preceding it is evident that compact units containing a minimum number of current sources may be made up so as to be easily attachable to any stringed instrument for sustaining the vibrations of its strings. Units can be made up of vibrator boxes and of current producing boxes and quickly assembled and attached to any piano.

The electromagnetic vibrators such as b¹ may be slidably mounted on appropriately designed base elements or boards and adjusted quickly on the latter in accordance with the spacing of the particular piano to which they are to be attached.

What I claim is:—

1. In an apparatus of the class described, the combination of a group of strings of different vibration frequency, means for producing a source of current having a wave form corresponding to the combined frequencies of all the strings, and means connected to said current source for vibrating any one string.

2. In an apparatus of the class described, the combination of a group of strings of different sounds having frequencies of vibration which are harmonics of some fundamental, means for producing a source of current having a composite wave form corresponding to the combined frequencies of the

strings and means connected to said current source for vibrating any single string.

3. In an apparatus of the class described, the combination of a group of strings of different vibration frequencies, means for producing a source of current having a composite wave form corresponding to the period of each of the strings in said group, a circuit connecting said current source to all of said strings, electromagnets for vibrating each string and switches for diverting current from the source into any electromagnet.

4. In an apparatus of the class described, the combination of a group of strings of different vibration frequencies, means for producing a source of alternating current having a wave form including the frequency of each string, electromagnets for vibrating the strings, switches for diverting current into the electromagnets, each of said switches and electromagnets being connected together in parallel across the terminals of the current source.

5. The method of producing sustained vibrations in stringed instruments which comprises the steps of producing a periodic electric current having a wave form which includes the periods of vibrations of a group of strings, in distributing this current to all the strings constituting the group, and in selecting from the composite source of current the frequency of current corresponding to the vibration frequency of any single string.

6. In an apparatus of the class described a group of strings having various vibration frequencies, means for producing a source of alternating current of desired wave-form, means for varying the wave-form of the alternating current produced by said last named means, a vibrator associated with each string, and means connecting said source of current to each vibrator.

7. In an apparatus of the class described a group of strings having various vibration frequencies, means for producing an alternating current having a wave-form including the vibration frequencies of each individual string, an electromagnet associated with each string, means for distributing the current produced by said first named means to each of said electromagnets, means operative to connect said source of current to any single electromagnet, and electromagnetic means for assuring a tuned relation between the current flowing to any single electromagnet and the vibration frequency of the string with which said electromagnet is associated.

In testimony whereof I have hereunto set my hand.

MARCEL TOURNIER.
